Primary Examiner — Celia Murphy*Assistant Examiner* — Clare Ann Gannon(74) *Attorney, Agent, or Firm* — Leber IP Law(57) **CLAIM**

The ornamental design for a belt, as shown and described.

DESCRIPTION

FIG. 1 is a top-left, front perspective view of the belt;
 FIG. 2 is a top plan view thereof;
 FIG. 3 is a front elevational view thereof;
 FIG. 4 is a bottom plan view thereof;
 FIG. 5 is a right side elevational view thereof;
 FIG. 6 is a left side elevational view thereof; and,
 FIG. 7 is a front perspective view of the belt as would be
 worn.
 The strap portions of the belt shown in broken lines in FIGS.
 1-7 do not form a part of the design. All other broken lines
 in FIG. 7 depict environment, which forms no part of the
 claimed design.
